DRIVER COMPARTMENT FOR A PSYCHO- PHYSICAL DRIVER TESTING UNIT

Herbert J. Sheppard, New York, N. Y.

Application May 25, 1956, Serial No. 41,656

Term of patent 14 years

(Cl. D25—1)

Fig. 1.

Fig. 2.

Fig. 1 is a front perspective view taken from the left side of a driver compartment for a psychophysical driver testing unit embodying my new design; and

Fig. 2 is a rear perspective view of the compartment as illustrated in Fig. 1.

I claim:

The ornamental design for a driver compartment for a psychophysical driver testing unit, as shown.
